INVENTOR

Salvatore Guzzomelzo

By W. W. Williamson
Atty.

UNITED STATES PATENT OFFICE.

SALVATORE GUZZO MENZO, OF PHILADELPHIA, PENNSYLVANIA.

FURNITURE CONSTRUCTION.

1,272,983.

Specification of Letters Patent. Patented July 16, 1918.

Application filed February 26, 1918. Serial No. 219,190.

To all whom it may concern:

Be it known that I, SALVATORE GUZZO MENZO, a subject of the King of Italy, residing at Philadelphia, in the county of Philadelphia and State of Pennsylvania, have invented new and useful Improvements in Furniture Construction, of which the following is a specification.

My invention relates to new and useful improvements in furniture construction and has for its object to provide a device of this character which may be of any desirable size, design, construction or form such as side boards, buffets, roll-top or flat desks or other similar pieces of furniture wherein the table portion may be projected to produce an extension table, but which when closed or collapsed will resemble the piece of furniture after the form of which it is constructed.

Another object of the invention is to provide leaf elements of a piece of furniture of unique construction, a number of which is utilized to produce an extension table, said leaf elements being connected with each other by means of flexible straps of any desirable material, each of said straps being attached to each leaf element at a single point adjacent one edge of the leaf element so that when the device is collapsed, closed or contracted the different leaf elements may lie upon one another in a relatively small space in the form of a cabinet or housing.

A further object of the invention is to provide in combination a cabinet for containing a number of leaves flexibly fastened together and a supplementary cabinet to which is fastened one end of the extension table made up of said leaves, said cabinet also having suitable supporting means connected therewith which is housed in said supplementary cabinet when the device is closed and which will be removed therefrom and properly positioned beneath the extension table as said supplementary cabinet is moved away from the main cabinet.

With these ends in view, this invention consists in the details of construction and combination of elements hereinafter set forth and then specifically designated by the claims.

In order that those skilled in the art to which this invention appertains may understand how to make and use the same I will describe its construction in detail referring

by numerals to the accompanying drawings forming a part of this application, in which—

Figure 1, is a perspective view of my improved furniture construction illustrating a final showing of cabinets and supplementary cabinets with portion of the different parts being broken away to clearly illustrate the construction.

Fig. 2, is an enlarged fragmentary perspective view of the main cabinet illustrating the different positions assumed by the leaves in being removed from or replaced in the cabinet with parts broken away to illustrate certain details of the construction.

Fig. 3, is an enlarged transverse sectional view of one of the leaves on the line of one of the tongues and grooves, and

Fig. 4, is a similar view on the line of one of the transverse slots.

In carrying out my invention as here embodied 2 represents a cabinet which may be of any suitable design, configuration, size or form and more particularly includes a back wall 3, a front wall 4, side walls 5, an inclined bottom wall 6 and a top wall 7 spaced from the upper edge of the front wall 4 to provide an opening or passage way 8 for the leaves of the extension table or extension top.

Within the cabinets are located suitable uprights or baffle members 9, the upper end of which terminates short of the top wall of the cabinet and the upper ends of said members are beveled inward and downward as at 10 and said members are secured to the back wall of the cabinet with their exposed faces preferably covered with a suitable soft material such as felt 11 so as to deaden the sound and prevent the leaves of the extension top or table from becoming scratched or otherwise marred and the back wall 3 of the cabinet is also preferably covered with suitable soft material such as felt indicated by the numeral 12.

Within the cabinet adjacent the passage way 8 and preferably attached to the front wall and side walls at each end of the cabinet is located a guide block 13 having an arcuate upper edge 14 and these guide blocks project rearwardly to a point short of an imaginary line projected upwardly from the front edges of the baffle members 9, so that the leaves of the extension table or top, as they enter the cabinet will be permitted to gradually descend and finally hang in a ver-

tical position at which time said leaves will pass down the faces of the baffle members, but when one leaf is in a horizontal position the next succeeding leaf is resting upon 5 the guide blocks in an inclined position so that said succeeding leaf will have to pass inward some distance before it takes a horizontal position and this inward movement will cause the lower edge of the leaf which 10 is hanging in a horizontal position to rest upon the inclined upper edges of the baffle members 9 and be guided thereby toward the front of the cabinet until the leaf which is resting upon the guide blocks has 15 moved or entered the cabinet a sufficient distance to permit the hanging leaf to rest upon the preceding leaf as plainly shown in Fig. 2.

The extension table or top designated by 20 the numeral 15 comprises any suitable number of relatively narrow leaves 16 which may also be of any desired length that will permit their entrance into the cabinet through the passage way 8. The longitudinal or 25 meeting edges of the leaves are beveled as at 17 so that said edges are parallel and the front edge of each leaf is beveled inward and upward while the rear edge is beveled inward and downward to be parallel therewith. Adjacent each end of each leaf is 30 formed a transverse slot or channel 18 and when in use the slots or channels of all the leaves at the same end are adapted to align and from one edge preferably the front edge 35 of each leaf projects a pair of tongues 19 which are adapted to register with suitable grooves 20 of the adjacent leaf, said grooves 20 being formed in the rear edges of each leaf. All of the leaves which are in use to 40 make up the extension table or top are connected together by flexible straps 21 of any suitable material such as leather or a textile fabric and these straps lie in the slots or channels and each strap is attached to each 45 leaf at one point only which is adjacent the forward edges of the leaves by some suitable means 22 such as for instance, a small screw as here shown.

The forward or outermost leaf is fastened 50 in some suitable manner to the supplementary or movable cabinet 23 opened at the rear, so that when said supplementary or movable cabinet is drawn away from the main cabinet, the leaves will be withdrawn 55 from the main cabinet to form the extension table or top and in order to support said extension table or top a suitable trestle work is provided which consists of the ordinary and well known extension table 60 slides 24 each succeeding one of which is located inside the preceding one so that they will collapse or slide within one another to produce a compact construction which will occupy a very small amount of space when 65 the device is closed. When a pair of these

slides is fixed to the main cabinet and properly braced by a cross piece 25 while every other pair of the other slides are secured to cross rails 26 to each end of which is fastened a leg 27 all of the legs on each side being in alignment so that when the device is closed, said legs and their cross rails as well as the slides will nest in the supplementary or movable cabinet 23 and since these parts will take up a relatively small amount of space in the supplementary cabinet the unoccupied space of said cabinet may be utilized as a closet or drawers may be arranged therein according to the form of the article of furniture produced or the desires of the 75 user.

In order that the legs and their cross rails will be properly disposed or positioned beneath the extension table or top according to the number of leaves in use, I provide a set 85 of lazy tons 28 one end of which is attached to the cross member 25 and the other end to some suitable part of the supplementary cabinet 23 while where the different members that make up the lazy tons cross each 90 other, they are pivoted to the different cross rails 26 as plainly shown in Fig. 1.

Presuming the device to be in a closed position then when it is desired to utilize the same as a table the supplementary or movable cabinet 23 is drawn away from the main cabinet 2 causing the leaves to be withdrawn from the interior of the main cabinet through the passage way 8 and as said supplementary cabinet is moved outward the 100 legs 27 are withdrawn from said supplementary cabinet with the leaves resting upon the slides 24 thereby properly supporting said leaves to produce a well braced and substantial top.

As the different leaves pass over the guide blocks 13, the tongues 19 of the succeeding leaves will register with the grooves 20 of the preceding leaves so that when the device is in an opened or extended position said 110 leaves will be locked together to prevent lengthwise movement of said leaves relative to each other which will keep the ends of all the leaves in proper alignment.

In order to close the device it is only 115 necessary to move the supplementary or movable cabinet 23 toward the main cabinet 2 causing the leaves to enter said main cabinet through the passage way 8 at which time the innermost leaf will be guided inward a sufficient distance by the guide blocks 13 and the baffle members 9 so that its inner rear edge will rest upon the rear part of the inclined bottom wall 6 against the vertical edges of the baffle members 9 and when a 120 sufficient number of leaves have entered the cabinet, said first leaf will rest entirely upon the inclined bottom wall after which the next succeeding leaf will be guided in the same manner until its inward or rear edge 125 130

rests upon the preceding or first leaf and this action of the succeeding leaf will cause the loose portions of the straps between the outer or rear edge of the preceding leaf to fold upon themselves as plainly shown and when the succeeding leaf takes its position upon the first or preceding leaf both layers of the folded portions of the straps will lie within the slots or channels of the succeeding leaf so that the under face of the succeeding leaf rests upon the upper face of the preceding leaf.

This action takes place with each leaf as it enters the cabinet with the possible exception of the last two or the two adjacent 15 the supplementary cabinet and in this case the one attached to the supplementary cabinet will rest upon the guide blocks while the next preceding leaf will be suspended therefrom and during this action of closing the device, the slides 24 will collapse or slide within one another until the cross rails 26 and the legs 27 contact with each other and when in this position, said slides, cross rails 20 and legs will be entirely inclosed in the supplementary cabinet 23 while said supplementary cabinet will be in close relation to the main cabinet so as to represent or produce the desired form of article of furniture and 25 the parts of the extension table or top will be entirely hidden from view.

Of course I do not wish to be limited to the exact details of construction as herein shown as these may be limited within the 30 limits of the appended claims without departing from the spirit of my invention.

Having thus fully described my invention what I claim as new and patentable is:—

40 1. In a device of the character stated the combination of a cabinet including front, back and side walls, an inclined bottom and a top spaced from the upper end of the front wall to form a passage way, vertical baffle 45 members having inclined upper ends secured to the back wall within the cabinet and terminating short of the top wall, a guide block located at each end of the interior of the cabinet adjacent the passage way, said guide 50 blocks having arcuate upper surfaces with the ends terminating short of the back wall, a covering of soft material on the back wall and edges of the baffle members, a supplementary cabinet open at the rear, a plurality 55 of leaves attached together by flexible means to form an extension top, one end of which is secured to the supplementary cabinet with the other end free to pass into and out of the main cabinet through the passage way, supporting means for the extension top adapted to be housed in the supplementary cabinet when the device is closed and means for positioning said supporting 60 means beneath the extension top when the device is opened.

2. In a device of the character stated the combination of a cabinet including front, back and side walls, an inclined bottom and a top spaced from the upper ends of the front wall to form a passage way, vertical 70 baffle members having inclined upper ends secured to the back wall within the cabinet and terminating short of the top wall, a guide block located at each end of the interior of the cabinet adjacent the passage 75 way, said guide blocks having arcuate upper surfaces with the ends terminating short of the back wall, a covering of soft material on the back wall and edges of the baffle members, a supplementary cabinet open at the 80 rear, an extension top comprising a plurality of leaves, each having a transverse slot or channel adjacent each end, provided with grooves in one edge and having tongues projecting from the opposite edge, the 85 tongues of leaves adapted to register with the grooves of coacting or adjacent leaves and flexible straps for attaching said leaves together, said straps lying in the transverse slots or channels and fastened at one point 90 to each leaf adjacent one edge thereof, one end of said extension top being secured to the supplementary cabinet with the other end free to pass into and out of the main cabinet through the passageway and means 95 for supporting said extension top in its extended position.

3. In a device of the character stated the combination of a cabinet including front, back and side walls, an inclined bottom and a top spaced from the upper end of the front wall to form a passageway, vertical baffle 100 members having inclined upper ends secured to the back wall within the cabinet and terminating short of the top wall, a guide block located at each end of the interior of the cabinet adjacent the passageway, said guide blocks having arcuate upper surfaces with the ends terminating short of the back wall, a covering of soft material on the back wall 105 and edges of the baffle members, a supplementary cabinet open at the rear, an extension top comprising a plurality of leaves each having a transverse slot or channel adjacent each end, provided with grooves in 110 one edge and having tongues projecting from the opposite edge, the tongues of leaves adapted to register with the grooves of coacting or adjacent leaves and flexible straps for attaching said leaves together, said 115 straps lying in the transverse slots or channels and fastened at one point to each leaf adjacent one edge thereof, one end of said extension top being secured to the supplementary cabinet with the other end free to 120 pass into and out of the main cabinet through the passageway, slides on which the extension top rests when extended, said slides being collapsible with the end ones attached to their respective cabinet, cross 125

130

4
rails fastened to certain of said slides, a leg at each end of each cross rail, all of said legs being in alinement and a lazy tong pivoted to each cabinet and to the different 5 cross rails for positioning the legs, cross rails and the slides.

4. An article of furniture comprising a cabinet including an inclined bottom wall, a plurality of leaves each having a transverse channel adjacent each end, flexible straps for connecting said leaves together, said straps lying in the grooves and being attached to each leaf at one point adjacent the forward edge, whereby when the leaves 10 enter the cabinet the portions of each strap underlying each leaf will fold upon themselves to permit each succeeding leaf to lie flat upon each preceding leaf with the double layers of the straps lying in the channels and means carried by one edge of each 15 20

leaf and coacting with the meeting edge of the adjacent leaf to lock said leaves against endwise movement.

5. In furniture construction, an extension top comprising a plurality of leaves with coacting parallel beveled edges, each leaf having a transverse channel in its under face adjacent each end and provided with interlocking means along its beveled edges and flexible straps lying in said channels and secured to each leaf at one point adjacent one edge whereby said leaves may be laid on top of one another with all top faces upward, the free portions of the straps under each leaf folding upon themselves and passing around one edge of each leaf as shown. 25 30 35

In testimony whereof, I have hereunto affixed my signature.

SALVATORE GUZZO MENZO.
